TUMBLE DISPLAY DEVICE

Howard W. Alton, Mount Prospect, Ill.

Application March 22, 1946, Serial No. 656,268

5 Claims. (Cl. 211—133)

1

My invention is concerned with improvements in a tumble display device for retail stores or the like.

In providing a display of merchandise, such as canned or bottled goods, for example, the retail storekeeper prefers a display device which is easily set up, which provides an attractive display of the goods, which requires a minimum arrangement of supporting means or the like, which is easily moved about and from which at least a portion of the goods may be sold without destroying the attractiveness of the display. The manufacturer or wholesaler who generally supplies the display device for the storekeeper prefers a device which will be acceptable to the storekeeper, which will provide an attractive display of the merchandise, which has adequate surface for printing or attaching advertising matter, which is readily collapsible for storage and shipment, and which will be rugged enough to stand a reasonable amount of use before it is discarded but which may be manufactured economically so that it is not too costly to replace the device with a new and possibly different one at frequent intervals.

It is an object of my invention to provide a display device which is adapted to be placed on the open top of a standard size case of merchandise such as canned or bottled fruits or beverages, and to receive therein an additional quantity of the merchandise for display without rearranging the merchandise in the case.

It is another object of my invention to provide a display device which may be made of cardboard or similar material, which may be collapsed for shipment or storage, which is readily set up for use and upon which advertising matter may be readily printed or attached.

These and other objects will be apparent from a description of the preferred form of my device which is illustrated by way of example in the accompanying drawings, wherein:

Fig. 1 is a perspective view of my display device positioned for display use on the open top of an empty carton or case;

Fig. 2 is a plan view of my display device arranged as in Fig. 1;

Fig. 3 is a front elevation of the same;

Fig. 4 is a rear elevation of the same;

Fig. 5 is an end elevation of the same;

Fig. 6 is a section on the line 6—6 of Fig. 2; and

Fig. 7 is a view showing the display device in knockdown and flattened condition.

As illustrated in Figs. 1 to 6 of the drawings,

2

the preferred form of my device comprises a generally vertical upwardly extending back panel member 10, a generally vertical downwardly extending front panel member 11, and spaced outer side or end walls 12 and 13 extending between and connecting the back panel 10 and front panel 11.

The front panel 11 is provided with an inwardly directed and downwardly sloping wall member 14 which terminates in a front flap member 15. The end walls 12 and 13 are provided with inwardly directed and downwardly sloping wall members 16 and 17, respectively, which terminate in end flap members 18 and 19, respectively. The sloping end wall members 16 and 17 are provided with connecting end tags 20 and 21 which are permanently secured to the sloping front wall member 14 by staples 22 or any other conventional fastening means.

End tabs 23 and 24 are provided on the front panel 11 adjacent the top edge or fold line 25, which are detachably secured to the end walls 12 and 13 by means of hook-shaped locking tabs 26 and 27 thereon engaging in the slots 28 and 29 provided in the end walls 12, 13. The end walls 12 and 13 are detachably connected to the back panel 10 by integral tabs 30 and 31 on the end walls engaging in cooperating slots 32 and 33 in the back panel 10. The sloping end walls 16 and 17 are detachably connected to the back panel 10 by integral tabs 34 and 35 on the walls engaging in cooperating slots 36 and 37 on the back panel. The back panel 10 is provided with a restricted lower portion or extension 38 which corresponds to the flaps 15, 18, 19 on the front and end wall members.

As shown in Fig. 7, the back panel 10 of my display device is constructed from a single blank and may be completely separated from the end wall members 12, 16, 18 and 13, 17, 19 by disengaging tabs 30, 31 and 34, 35 from the slots 32, 33 and 36, 37. The front portion of my device is formed from a single blank and provided with the score lines 25 and 39 on which the blank is folded to provide the wall members 11, 14 and 15. The ends of the device are formed from separate blanks and provided with the score lines 40, 41, 42 and 43, 44, 45. The end members 16 and 17 are permanently connected to the front wall member 14 by stapling the connecting tabs 20, 21 to the ends thereof.

When disassembled the ends may be folded along the score lines 42 and 45, onto the front members 11, 14 and 15 for packing or storing. When erected for display use the folds 25, 40

and 44 become the top front and end edges of the device and the folds 39, 41 and 43 form the lower limits of the front and end inner sloping walls 14, 16, 17. The connecting tabs 23, 24 are folded on the lines 46 and 47 to permit insertion of the locking tabs 26, 27 in the slots 28, 29 to secure the front panel 11 in position.

In use my device is assembled and placed on the open top of a carton or box 46 of merchandise with the flap members 15, 18, and 19 and the back extension 38 positioned between the contents of the carton or box 46 and the walls of the same. The contents of the supporting carton or box 46 may remain undisturbed as illustrated in Fig. 6. The sloping walls 16, 17 and 19 form a funnel-like extension for the carton 46 and additional merchandise may be tumbled or piled therein.

Any or all of the walls of the device may be printed or otherwise supplied with advertising matter relating to the merchandise on display. The merchandise may be sold directly from the display device and the supply of the same replenished, as needed, without detracting from the effectiveness of the display. The device is dimensioned so that it will fit on the standard size cartons conventionally used. The front and back panels 10 and 11 may be varied in height or shape, if desired, to meet particular conditions or requirements and to adapt the device to various kinds of merchandise. While the front and back panels 10 and 11 are illustrated as extending substantially vertically, it is understood that they may be sloped, if desired. The top end edges 40, 43 of the illustrated form of my device slope somewhat inwardly and downwardly toward the front of the device to better display the merchandise placed therein.

In describing the preferred form of my device I have referred to specific details of construction and materials, but it will be understood that other forms of construction and other materials may be resorted to within the scope of my invention.

I claim:

1. A tumble display device comprising a generally vertical front panel, a generally vertical back panel, spaced outer end panels connecting the front and back panels, sloping inner walls extending inwardly and downwardly from the top of the front panel and the tops of the end panels terminating in flap members, a downwardly directed flap-like portion on said back panel, said sloping inner walls and flap members cooperating with said back panel and its flap-like extension to form a funnel-like receptacle adapted to be placed on the open top of a case of merchandise with the flap members disposed adjacent the inner side walls of the case and to receive for display therein additional merchandise.

2. A tumble display device comprising a back panel having a downwardly directed flap-like lower extension adapted to be positioned within a rectangular open top merchandise container in contiguous relation to a wall thereof, a front panel having an inwardly and downwardly directed sloping inner wall member terminating in a downwardly directed flap member; said flap member being adapted to be positioned within said merchandise container in contiguous relation to a wall opposite to the wall receiving said back panel, extension side panels connecting said front and back panels and having inwardly and downwardly directed sloping inner wall members terminating in downwardly directed flap members, said flap members being adapted to be positioned within said container against the remaining walls thereof, said inner wall members adapted to extend above said merchandise container and cooperating with said back panel to form a display receptacle for receiving additional merchandise.

3. A tumble display device comprising a generally vertical front panel, a generally vertical back panel, spaced outer end panels and sloping inner front and end walls, said outer end panels connecting said front and back panels, said inner walls extending inwardly and downwardly from the tops of said outer front and end panels and terminating in flap members, said inner walls and their flap members cooperating with the lower portion of said back panel to form a funnel-like receptacle adapted to be placed on the open top of a case of merchandise with the flap members disposed adjacent the inner side walls of the case to receive for display therein additional merchandise.

4. A tumble display device as recited in claim 3 wherein the outer end panels and the inner end walls are detachably connected to the back panel.

5. A tumble display device as recited in claim 4 wherein the outer end panels are detachably connected to the front panel and the inner end walls are hingedly connected to the inner front wall.

HOWARD W. ALTON.
